UNITED STATES PATENT OFFICE.

WILHELM KUMMERER, OF BERLIN, GERMANY, ASSIGNOR TO GESELLSCHAFT FÜR DRAHTLOSE TELEGRAPHIE M. B. HALLESCHES, OF BERLIN, GERMANY, A CORPORATION OF GERMANY.

TRANSFORMER.

Application filed August 18, 1925, Serial No. 50,981, and in Germany September 9, 1924.

My invention relates to a device for converting alternating current of one potential to alternating current of the same or different potential, known in the art as transformers.

My invention relates more particularly to a transformer which must withstand a high direct current potential between primary and secondary windings.

10 An object of the invention is to provide a transformer of the above described kind which will not break down on high direct current voltage, will not unduly heat up, and yet will be cheap to manufacture, take 15 up but a small space and be efficient in use.

Other objects will be apparent from the following description and appended claims when considered with the accompanying drawing which represents an embodiment of 20 my invention.

In using rectifiers comprising an incandescent cathode as, for instance, a high-vacuum rectifier, or a Wehnelt rectifier, in the case of connections of the kind employed 25 with electron discharge tube transmitters, it has been found that the heated filaments of the rectifiers possess the full direct current potential to ground. In the case of rectifiers worked with high direct current 30 potentials as, for instance, of the order of 10,000 volts, it is therefore necessary that a transformer for a comparatively small energy must be provided with sufficient insulation, however, between primary and sec- 35 ondary to withstand 10,000 volts, while the alternating current voltage in the secondary winding ranges mostly only between 10 and 20 volts.

The usual form of construction of trans- 40 formers with a solid insulator between primary and secondary winding as presspahn, micanite, etc., therefore leads to frequent breakdowns, since the insulation material is subject to slow destruction under the action 45 of the direct current potential due to electrolytic effects. The danger existing for transformers is intensified owing to the fact that in transmitters more or less high frequency potentials arise frequently between 50 the primary and the secondary winding, and the dielectric losses caused thereby result in marked heating of the insulation. Another point is that overvoltages can not be completely precluded under practical 55 working conditions.

Now the subject matter of the present invention consists of a transformer which is constructed to withstand the said stresses, while it is subject to little stray, and is of small dimensions. The essential feature of 60 the new arrangement resides in that between the windings, no solid insulation is provided, and also in that the secondary winding carrying high potential direct currents is carried by high voltage insulators which 65 can be made of a material which is not hygroscopic or heat-sensitive. A particularly important point in this arrangement is that the primary winding is screened or shielded by the aid of a sheet metal cylinder. 70

My invention is illustrated in the accompanying drawing which shows a side elevation, partly in section, of my new improved transformer.

Referring now more particularly to the 75 drawing, 1 is the iron core on which is placed an insulating cylinder 2 which carries the primary winding 3. The said primary winding is brought out to the two terminals 4 and 5. The secondary winding which is de- 80 noted by 6 is wrapped on a cylindrical bobbin or coil tube 7 made of metal. Tube 7 is supported solely by the high tension insulators 8 and 9 by means of rod 26. Insulators 8 and 9 rest upon the magnetic core 1. The secondary winding 6 is therefore arranged to freely surround the primary winding 3 without any other dielectric than air being em- 85 ployed for insulating purposes. The ends of the secondary winding 6 are brought out to 90 terminals 24 and 25.

Placed directly over the primary winding 3 is the sheet metal cylinder 10 which is conductively connected with a convenient point of the primary winding. Another essential 95 point is that the metallic tube 7 of the high tension winding 6 is in single point connection with the secondary winding 6. As a consequence, resulting from the cylindrical construction of the coils, there is obtained an 100 entirely uniform direct current electrostatic field between tubes 7 and 10. Hence, a relatively small distance between the two tubes will suffice in this arrangement.

If the sheet metal tube 10 were omitted, 105 irregularities in the smoothness of the winding 3 might result in a breakdown even at much lower potential differences. In addition, the arrangement offers this further substantial advantage that the transformer in 110

the case of excess voltage flashes over between the metallic tubes 7 and 10 without causing damage to the winding of the transformer as a consequence. To avoid eddy currents, the metal tubes 7 and 10 are split, as indicated at 21 and 22.

It goes without saying that the entire transformer, for the purpose of more efficient cooling, and to increase the puncturability, may be immersed in oil or any other desirable cooling liquid in well known manner.

Having described my invention, I am entitled to all modifications thereof as fall fairly within its spirit and scope, as defined by the following claims:

1. A transformer comprising, a magnetic circuit, a tube of insulation surrounding a portion of said circuit, a first winding surrounding said tube of insulation, a first metal tube surrounding said first winding, post insulators resting upon said circuit, a second metal tube supported by said insulators, said second metal tube surrounding and being in spaced relation to said first winding, and a second winding surrounding said second metal tube, said metal tubes being split longitudinally.

2. A transformer comprising, a magnetic circuit, a first winding surrounding a portion of said circuit, a first metal tube sur-

rounding and connected to a point of said first winding, post insulators resting upon said circuit, and a second winding supported by said insulators, said second winding surrounding and being in spaced relation to said first winding.

3. A transformer comprising, a first winding, a first metal tube surrounding and shielding said first winding, a second metal tube surrounding and being in spaced relation to said first winding, a second winding surrounding said second metal tube, and means for supporting said second metal tube in spaced relation to said first winding, whereby there is no solid dielectric between said windings.

4. A transformer for low alternating current potentials, in which under normal working conditions there exists a high potential difference between the primary and secondary windings, comprising a low tension winding, a high tension winding, a cylindrical metal body adapted to support said high tension winding and insulators supporting said body in spaced relation to said low tension winding.

5. The transformer according to claim 4, including a split sheet metal cylinder adapted to screen the low potential winding and in conductive connection therewith.

WILHELM KUMMERER.
